UNITED STATES PATENT OFFICE.

ROBERT LEVY, OF BERLIN, GERMANY.

LAMP SHADE.

Application filed May 18, 1925, Serial No. 30,964, and in Germany November 12, 1924.

The present invention has for its object a lamp-shade which, although of simple construction, allows to open and close the shade, in case of requirement, to concentrate the 5 light rays on a small place, or to distribute them on a larger surface. The well known method, as used for umbrellas, cannot be used for the present invention as the articulated stays, necessary for the opening and 10 closing of an umbrella, would throw bothersome shadows and do not give a nice appearance to the cloth-cover at different adjustments. In the present invention stays are utilized as carriers for the cloth-cover 15 which are connected with an adjusting device, by means of convenient arrangements, so that bothersome shadows cannot occur.

To attain this several arrangements can be used. In every case levers are used, which 20 serve as cloth carriers, and which are connected with an adjusting device by means of an organ of some kind.

The invention is illustrated in the accompanying drawings, in which:—

25 Fig. 1 is a form of construction of the shade, in section.

Fig. 2 a second form of construction, also in section.

Fig. 3 a further form of construction.

30 Fig. 4 a form of construction in which the carriers are elastic.

Fig. 5 a form of construction in which the carriers are spring-controlled.

35 Fig. 6 a further form of construction in which the shade is controlled by a central spiral spring.

Figs. 7 and 8 a still further form of construction.

The stays *a* which serve to carry the cloth 40 cover, for instance silk, are preferably made of wire and oscillably mounted on an axle *c* arranged on the ring *b*, the latter receiving its support by means of radial stays (not shown) which are carried by a stationary 45 rod *g*.

In the form of construction shown in Fig. 1, the stays *a* are constructed as angle levers, the shorter arms *a'* of which, are led, by 50 means of thin strings *d*, to a guide ring *e* having a clamping screw *f*. After unscrewing the clamping screw *f* the guide ring *e* can be moved along the stationary bar *g*. When pulling the ring *e* downwards, the 55 levers *a* swing outwards around the axle *c* of ring *b* so that the shade opens and the cloth-covering lights a larger surface than if

one would leave the ring *e*, after unscrewing of the screw *f*, slide upwards under the weight of the levers *a*, which would automatically fall into the position shown in dotted lines. The stays *a*, and consequently the whole shade, can be adjusted in any intermediate position by means of the screw *f*. In the form of construction shown in Fig. 1 a heavy chain or like pulling organ must 60 be provided for every angle lever *a*, *a'*.

In the form of construction shown in Fig. 2 the provision of heavy chains or the like is not necessary as the short arms *a'* of the angle levers *a*, *a'* are connected by means of 65 a small chains *h* to a special ring *i* which is fixed to the lower ends of the small chains *h* and in this manner communicates with the angle levers *a*, *a'*. The ring *i* can be connected with the adjusting device *e*, *f* 70 through the intermediary of a conical glass-shade *k*. This glass-shade made of milk-glass or transparent material, can be replaced by two strings.

In the form of construction shown in Fig. 3 no angle levers are used but the corresponding bent levers *a* are oscillably mounted on the axle *c* of ring *b* and rest with their free ends on the rim of ring *i*. The ring *i* can be lifted with the aid of the translucent 80 shade *k* to bring the lamp shade from the position shown in full lines into the position shown in dotted line, in which case the levers *a* will follow the movement and come into the desired stretched or open position. Also 85 in this form of construction any intermediate position can be adjusted by means of the clamping device.

In the form of construction shown in Fig. 4, levers *a* of elastic material are used in the 90 upper ends of which are fixed on the ring *b*. This fixation can for instance be done in such a manner that the levers *a* are shifted or clamped into convenient clamps *b'*. The levers or stays can be made of steel, whale-bone or other bending or elastic material. In proximity of the free ends of the levers *a* pull-strings *d* are fixed which are conducted 100 through eyes *g'* of a stationary plate or ring *g*. The free ends of the pull strings *d* are fixed on a disk *l* which carries a ratchet pawl *l'*. This ratchet pawl can engage with the teeth *g* provided in the stationary bar *g*. The ratchet pawl is spring-controlled and 105 with the aid of a chain *m* the locking mechanism of the pawl can be released at any time. The ratchet being released, the disk *l*

can be pulled down by means of the chain *o* to bring the stays *a* into the position shown in dotted line and consequently close the shade more or less. In releasing the 5 ratchet pawl *l'* through the intermediary of the chain *m*, the elastic stays will automatically go back to their normal position, which is shown on the drawings in full lines, and the shade is opened. The disk *l*, with 10 ratchet pawl, can be operated in any intermediate position so that the shade is locked as required.

Instead of making the stays from elastic material, they can be made, as shown in Fig. 15, from rigid material and controlled by springs *n* which have the tendency to bring the stays *a* into the open position.

The adjusting device is in this case constructed in the same manner as in Fig. 4.

20 In the form of construction shown in Fig. 6 the springs *n* do not directly come in touch with the levers *a* but control a disk *p* which communicates by articulations with the levers *a*. The chains *m* and *o* have in this 25 case the same functions as in the form of construction shown in Fig. 4. Through the chain *m* the ratchet *l'* is released and by pulling chain *o* downwards, against the action of the spring *r*, the shade is more or 30 less closed, opening automatically when releasing the ratchet.

Fig. 7 shows a form of construction in which, instead of swinging levers, wire bows *a⁵* are used which can be adjusted, quite as 35 the levers *a*, with the aid of a pulling device. The bows are covered with a transparent material, for instance galalith-glass, galalith, or the like, and between the several bows, cloth, for instance silk, is stretched by 40 means of which a very effective light is produced. This effective light can be produced on a smaller or larger surface.

I claim:—

1. A lamp shade, comprising in combination a stationary ring, cloth carrying levers 45 mounted to oscillate on said ring and

adapted to normally fall downwardly by their own weight means comprising a ring operating to oscillate said levers and adjust the same in stretched position, and spring 50 members operating said means.

2. A lamp shade, comprising in combination a stationary ring, cloth carrying levers mounted to oscillate on said ring and adapted to normally fall downwardly by 55 their own weight means operating to oscillate said levers and adjust the same in stretched position, spring members operating said means, and a pawl and ratchet to adjust the means in any desired position. 60

3. A lamp shade, comprising in combination a stationary ring, cloth carrying levers mounted to oscillate on said ring and adapted to normally fall downwardly by 65 their own weight means comprising a ring operating to oscillate said levers and adjust the same in stretched position, spring members operating said ring, a pawl and ratchet to adjust the ring in any desired position, and a guide bar provided with teeth to receive the said pawl. 70

4. A lamp shade, comprising in combination a stationary ring, cloth carrying bow-shaped levers mounted to oscillate on said ring and adapted to normally fall downwardly by 75 their own weight means comprising a ring operating to oscillate said levers and adjust the same in stretched position, and spring members operating said means.

5. A lamp shade, comprising in combination a stationary ring, cloth carrying bow-shaped levers mounted to oscillate on said ring and adapted to normally fall downwardly by their own weight, means comprising a ring operating to oscillate said levers 80 and adjust the same in stretched position, spring members operating said means, and a transparent material covering said bows. 85

In testimony whereof I affix my signature.

ROBERT LEVY.
